(57) **CLAIM**

The ornamental design for a file rack, as shown and described.

DESCRIPTION

FIG. 1 is a perspective view of a file rack showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view showing a status before the file rack is fixed on a base by fasteners;

FIG. 9 is the other perspective view with the file rack being fixed on the base by the fasteners;

FIG. 10 is the other perspective view with additional two file racks being fixed on the base by additional fasteners; and, FIG. 11 is an enlarged view of an indicated portion of FIG. 10.

The broken lines are included to show portions of the file rack that form no part of the claimed design.

1 Claim, 9 Drawing Sheets
